Primary Examiner — Dana K Weiland*Assistant Examiner* — Messina L Smith(74) *Attorney, Agent, or Firm* — Stephen J. Stark; Miller & Martin PLLC(57) **CLAIM**

The ornamental design for a grill pan, as shown and described.

DESCRIPTION

FIG. 1 is a perspective view of a grill pan, showing the new design;

FIG. 2 is a top elevational view thereof;

FIG. 3 is a left side elevational view thereof;

FIG. 4 is a right side elevational view thereof;

FIG. 5 is a rear elevational view thereof;

FIG. 6 is a front elevational view thereof; and,

FIG. 7 is a bottom elevational view thereof.

The broken lines shown in the drawings depict portions of the grill pan that form no part of the claimed design.
